FIG. 2

FIG. 3

FIGURE 1 is a perspective view of a portable rest mat showing my new design, in which the mat is extended for use.

FIG. 2 is a perspective rear view of a portable rest mat of FIG. 1 in which the mat is folded or collapsed; and

FIG. 3 is a perspective front view of the mat in its folded or collapsed condition.

The characteristic features of my design reside in the portion shown by means of full lines in the drawing.

I claim:

The ornamental design for a portable rest mat, substantially as shown and described.
